Attorney.

UNITED STATES PATENT OFFICE.

CHARLES H. WEAVER, OF HORNELLSVILLE, NEW YORK, ASSIGNOR OF ONE-HALF TO HAMILTON G. PRESTON, OF SAME PLACE.

PIPE-WRENCH.

SPECIFICATION forming part of Letters Patent No. 516,249, dated March 13, 1894.

Application filed July 10, 1893. Renewed February 6, 1894. Serial No. 499,303. (No model.)

To all whom it may concern:

Be it known that I, CHARLES H. WEAVER, a citizen of the United States, residing at Hornellsville, in the county of Steuben and State of New York, have invented certain new and useful Improvements in Pipe-Wrenches, of which the following is a specification, reference being had therein to the accompanying drawings.

10 My invention relates to pipe wrenches, and has for its object to provide a wrench which has a tendency to grip the pipe the tighter as more power is applied to the handle thereof, and to provide a wrench of this character 15 with a spring operating on the jaws of the wrench in such a manner as to give the initial grip on the pipe before power is applied to the wrench handle, and thus avoid a tendency of the wrench to slip when the jaws are 20 closed on the pipe.

In the accompanying drawings, Figure 1 represents my improved wrench with the jaws grasping a piece of pipe, and Fig. 2 represents the same with the jaws closed.

25 A denotes the handle of the wrench to one end of which, at a, is pivoted the jaw-lever B provided with a gripping jaw b.

C denotes the other jaw-lever provided with a gripping jaw c, the two levers being pivotally attached together at c'.

30 D is a lever pivoted at d to the handle A and jointed at d' to the rear end of the jaw-lever C, the lever D being pressed upon at its end opposite that where it is pivoted to the jaw-lever C by a spring E which is attached to the handle A. The spring E presses upon the end of the lever D in such a manner as to have a tendency to close the jaws of the

wrench, and it will therefore be apparent that when the serrated wrench jaws are made 40 to embrace a pipe, as shown in Fig. 1, the said spring will press upon the said jaws together in such a manner as to give an initial grip on the pipe, this being done before power is applied to the handle A to cause the jaws 45 of the wrench to grip the pipe with force enough to turn it.

From the foregoing it will be apparent that I am enabled to provide a pipe wrench which is simple in construction, and efficient in operation, and which can be used with a greater ease and convenience than other similar wrenches heretofore produced, for the reason that the tendency of the wrench to slip on the pipe is greatly lessened or entirely avoided. 55

Having thus described my invention, I claim and desire to secure by Letters Patent—

The combination with the handle A, of the jaw-lever B pivotally attached thereto and 60 provided with the jaw b, the jaw-lever C pivotally connected with the said jaw lever B, and provided with the jaw c, the lever D pivoted to the said handle A and jointed to the said jaw-lever C, and the spring E attached 65 to the said handle A and arranged to press upon the said lever D in such a manner as to have a tendency to force the jaws of the wrench toward each other.

In testimony whereof I affix my signature in 70 presence of two witnesses.

CHARLES H. WEAVER.
